TELETYPEWRITER

Charles R. Doty, Yonkers, N. Y., assignor to International Business Machines Corporation, New York, N. Y., a corporation of New York

Application November 9, 1939, Serial No. 303,526

1 Claim. (Cl. 197—19)

This invention relates to typewriters and, more particularly, to typewriters adaptable for use as translating units in remotely controlled printing telegraph systems and the like.

It is the general object of the present invention to provide a simplified and improved permutation bar system associated with the character keyboard of a typewriter and adapted to operate the key levers in accordance with permutation or combinational signals received.

More specifically, it is the object of the invention to provide a mechanical permutation bar system of unique construction and with an improved electrical readout for special uses such, for example, as operating the key levers of a typewriter.

Other objects of the invention will be pointed out in the following description and claim and illustrated in the accompanying drawings, which disclose, by way of example, the principle of the invention and the best mode, which has been contemplated, of applying that principle.

In the drawings:

Fig. 1 is a cross sectional view of one type of power operated typewriter and the associated permutation bar unit.

Fig. 2 is a sectional view showing the controlling clutch and magnets of the permutation bar unit.

Fig. 3 is an exploded view of the permutation bar clutch unit.

Fig. 4 is a detail view of the drive gears for the bars.

Fig. 5 is a schematic diagram of the simple operating circuits of the machine.

Figures 6 to 6B are detail views of the clutch unit.

For illustrative purposes, this invention is shown as embodying a well known form of recording unit, which may be the Electromatic typewriter shown in Patent No. 1,777,055, and hence requires only the following brief description.

Referring to the drawings and particularly to Fig. 1, in the embodiment illustrated in the drawing well known means are provided for actuating the type bars (not shown) by power operated devices comprising a power driven roller 10.

A cam 11 is pivoted on one arm of a bell crank lever 12 pivoted in the frame, the other arm of which is operatively connected with one arm of a bell crank lever 13 by means of link 14. The other arm of lever 13 is connected to the type bars (not shown) in a well known manner.

The lever 12 is actuated by the cam 11 when

the latter engages the driven roller 10 to be operated thereby. The engagement of the cam 11 with the power roller is controlled by means of the key lever 17 in a manner which will now be described.

The cam 11 is resiliently engaged by a spring-pressed arm 20 which tends to turn it into engagement with the power driven roller or a stop 21 on a lever 22 pivoted on the bell crank 12 and normally arranged in the path of a lug on the cam. When the lever 22 swings to move its stop out of the path of the lug, the arm 20 swings the cam into engagement with the power roller to be actuated thereby to swing the bell crank 12 to actuate its connected mechanism.

The lever 22 has an arm 24 which is provided with an offset projection 25 at its end which projects laterally through an opening in the bell crank 12 and engages the bifurcated lower end 26 of an arm 27 of a key lever 17 pivoted on the common rod 28.

It is obvious then that depression of a key lever 17 releases the revolvably mounted cam 11 to engage and be actuated by power roller 10 in turn operating bell crank 12 and its attached links to cause the associated mechanism, such as the type bars and other operating mechanism, to be operated.

Actuating means for the key levers 17 is provided in the form of individual solenoids 30 which have their armatures 31 connected by a link 32 to the respective key levers 17 in such a manner that upon energization of the solenoids, the key levers are operated.

The permutation bar mechanism associated with the key levers for controlling the energization of the key lever solenoids is shown in the drawings to comprise generally a plurality of slotted shafts or bars 35 having an elongated, cam shaped cross section, the slots 36 of which are cut in the upper portions of the bars as best illustrated in Fig. 3. The bars are normally maintained inoperative so that seeker levers 37, one for each key lever, are locked in an inoperative position by engagement with the high portions of certain of the bars. Gear units 41 (Fig. 4) are provided at each end of the permutation bar device, comprising three sets of gears, one for each shaft or bar 35. The gears 38, 39, and 40 are rotated continuously by drive gears 42 and are connected to the associated bars 35 by individual clutches 43 (Fig. 3) to drive said bars one revolution. The clutches 43 are controlled by magnets 44 which are energized by control signals and in combinations in accordance with

the preferred permutation code. During the rotation of the selected bars 35 the high portions of these bars are removed from the path of the seeker levers 37 so that one seeker lever is selected and permitted to drop in the channel provided by certain of the slots 36 in the bars remaining stationary, thereby operating the selected seeker lever and its attached key lever and causing the corresponding character to be recorded.

The permutation bars 35, of which six are shown, are supported in the end plates 45 (see Fig. 2) attached to the gear units 41 which are secured to the supporting casting indicated generally at 46. The seeker levers 37 are positioned over the permutation bars 35 and are pivotally supported at the ends thereof by rod 48 suitably carried by members 49 mounted on the adjacent casting 46. Individual springs 50 are attached to the levers 37 to urge the levers against the permutation bars 35. The levers 37 at their other ends are arranged to operate individual sets of contacts 37a. Thus, it will be seen that upon depression of a seeker lever 37 by spring 50, the related contacts 37a will be moved to a closed position by virtue of a camming action exerted by the seeker lever in its downward movement. The levers 37 are kept in correct alignment by means of the comb member 54 attached to the said supporting casting. Closure of any of the sets of contacts 37a brings about the energization of one of the key lever solenoids 30 as is obvious from Fig. 5. Each of the solenoids 30 upon becoming energized attracts its armature 31 which is connected through link 32 to a key lever 17, thereby causing lever 17 and its associated type bar to be operated.

The permutation bars are slotted in accordance with any desired permutation code, the slots as shown being arranged so that upon rotation of certain of the bars, one seeker lever 37 is selected and permitted momentarily to be depressed into the slots by spring 50 thereby actuating the associated contacts 37a and key lever 17.

The bars are connected for rotation by the power driven roller 18 of the typewriter by reason of a connecting belt 56 which rotates shaft 55. Attached to shaft 55 is a pair of driving gears 42, the gears positioned so as to engage the gears 38 (Fig. 4) in each gear unit 41. The gears 38 are adapted to rotate the gears 39 and 40. The gears 38, 39, and 40 are attached to individual stub shafts 56 (Fig. 3) upon which are mounted ratchet gears 57. Associated with each ratchet gear 57 is a clutch unit 43 which is secured to the permutation bar 35. A clutch unit is provided for each bar. The principles of operation of the sets of clutch units and gear units are identical and consequently only one set need be explained. It will be seen from Fig. 4 that the directions of motions of the clutch gears 38, 39, and 40 are different, and because of this fact the clutches 43 are made right-hand and left-hand to correspond thereto.

A controlling magnet 44 is provided for each clutch 43. Referring to Figs. 3 and 5, the magnet 44 is provided with an armature 60 secured to a clutch stop arm 61. The said arm, while the magnet 44 is deenergized, is adapted to engage the dog lift lever which maintains the dog 63 in the position shown in the figure to prevent engagement of the tooth 64 on the dog and the ratchet gear 57.

The clutch is shown to comprise (see Figs. 6 to 6B) a housing member 65 secured to the permutation bar 35. The member 65 is shaped so

as to receive the toothed dog 63. A spring post 66 is fixed in the said member 65 and acts as a guide for spring 68. The dog 63 is shaped so as to fit over the said spring and spring post and when mounted in the channel provided in the housing member 65 it is seen that the spring 68 tends to urge or maintain the dog 63 to the right as viewed in Fig. 6A. The dog 63 and housing member 65 are recessed so as to receive the dog lift lever 62 which when inserted in the housing member is adapted to be rotated slightly or pivoted about one end thereof. The other end of the dog lift lever extends beyond the housing member and is arranged to engage the stop arm 61 whenever magnet 44 is deenergized. Movement of the dog lift lever 62 moves the recessed dog 63 and when blocked by the stop arm 61 as shown in Fig. 3 positions the dog 63 to the extreme left-hand position against the action of spring 68. A spring-pressed stop 67 engages a notch 68 provided in the housing member 65, the bar 35 to be rotated in a counter-clockwise direction as viewed in the figure, thereby also locking the clutch unit 43 so long as the magnet 44 remains deenergized.

Upon energization of the magnet, its armature 60 is attracted and positions the stop arm downwardly about the pivot 69 and out of engagement and the path of dog lift lever 62. The spring 68 then forces the dog 63 to the right as viewed in Fig. 5 into engagement with the constantly rotating ratchet gear 57.

The signal condition impressed upon the magnet 44 lasts momentarily, so that the stop 61 is positioned in the path of the dog lift lever 62 before one revolution of the clutch has been completed. As the clutch is rotated by the gear 57 and completes its revolution the dog lift lever engages the stop 61, and as the clutch continues its rotation with the lift lever 62 held stationary by the stop 61, the said lift lever is rotated about its end positioned in the housing member 65 to slide the toothed dog 63 out of engagement with the ratchet gear 57. When the tooth 64 is brought out of engagement with the said ratchet, driving power is removed from the clutch and permutation bar. The spring 68 within the dog 63 normally would have a tendency to rotate the permutation bar in a reverse direction and permit the tooth 64 to again engage the ratchet gear; however, as previously explained the clutch and bar 35 are locked in the inoperative position by means of the stop 67. Due to the relative high speed of operation, when the toothed dog is forced out of engagement with the ratchet by means of the stop 61, the momentum of the rotating permutation bar and clutch is sufficient to rotate the bar and clutch slightly beyond the position where the tooth 64 just becomes disengaged from the ratchet gear; this carry-over is sufficient to permit the spring-pressed stop 67 to engage the notch 68 locking the clutch and bar against reversed rotation and insuring sufficient clearance between the dog tooth and the ratchet so as to prevent chattering.

The remaining permutation bars are rotated in a like manner upon energization of the associated clutch magnets 44. The magnets are energized practically simultaneously so that when a particular combination of signals causes certain of the magnets to be energized, the corresponding permutation bars are permitted to be rotated one revolution, permitting one seeker lever 37 to drop in the aligned slots on the permutation bars which have remained stationary, thereby

actuating a set of contacts 37a to cause recording of a character on the power operated typewriter accordingly in the manner described previously herein.

The design of the bars and seeker levers of the permutation bar unit is such that a long duration of closure of any of the contacts selected for operation is assured. Downwardly extending tab portions are provided on the levers 37 and these portions facilitate the cooperation of the levers with certain of the slots 36 of bars 35 as previously described. The elongated cross section of the bars supplies a long dwell which permits the selected seeker lever to remain in its operated position for the greater part of a revolution of the rotated bars. The selected seeker lever thus holds the contacts 37a closed for the period in which the long dwells of the rotating bars are moving by the lever, which period is sufficiently great to adequately energize the proper key lever solenoid 30. The bars may be made round instead of oblong in cross-section but if this is done, the speed of operation would necessarily be more limited because of a shorter duration of closure of the contacts 37a during each revolution of the bars. The slots 36 are cut in the top of all the bars and, with the clutches latched up, these slots stand ready to receive their related seeker levers immediately upon rotation of predetermined combinations of bars 35 in accordance with the preselected permutation code. At the end of one revolution, the bars are restored to their normal position. Thus it is seen that upon reception of a signal the bars are rotated, but even in this event all the seeker levers are maintained in a locked position except the selected one, in this manner making it impossible to depress more than one seeker lever or to operate more than one set of contacts 37a or more than one key lever 17 at a time.

While there has been shown and described and pointed out the fundamental novel features of the invention as applied to a single modification

it will be understood that various omissions and substitutions and changes in the form and details of the device illustrated and in its operation may be made by those skilled in the art without departing from the spirit of the invention. It is the intention, therefore, to be limited only as indicated by the scope of the following claim.

What is claimed is:

A character translating device of the class described comprising, in combination, a keyboard having a plurality of key levers one for each character, individual electromagnets for operating said key levers, a plurality of rotatable permutation elements each having an elongated cross-section in the shape of a cam with a single high portion and a long dwell, said elements being provided with transverse slots cut at predetermined locations along the high portions of their peripheries, a plurality of seeker levers each aligned with a slot in predetermined ones of the permutation elements but normally withheld from said slots by the high portions of the peripheries of others of said elements, means to rotate predetermined combinations of the permutation elements in accordance with the characters to be translated to select said seeker levers for operation by removing the high portions of the rotated elements from the paths of predetermined ones of the seeker levers to cause the selected levers to seek the slots in the elements remaining stationary with which the latter levers are aligned, and individual circuits for energizing the magnets to operate the related character key levers including circuit-closing means rendered effective by the operated seeker levers for the predetermined period during which time the long dwells of the rotated permutation elements are moving by said selected seeker levers, said period being of sufficient duration to insure positive energization of the magnets in the circuits rendered effective by said seeker levers.

CHARLES R. DOTY.
